UNITED STATES PATENT OFFICE

JOHN T. ESTABROOK, OF SIDNEY, OHIO.

CHURN.

SPECIFICATION forming part of Letters Patent No. 243,230, dated June 21, 1881.

Application filed November 16, 1880. (No model.)

To all whom it may concern:

Be it known that I, JOHN T. ESTABROOK, of Sidney, in the county of Shelby and State of Ohio, have invented certain new and useful 5 Improvements in Churns; and I do hereby declare that the following is a full, clear, and exact description of the invention, which will enable others skilled in the art to which it appertains to make and use the same, reference 10 being had to the accompanying drawings, which form a part of this specification, and in which—

Figure 1 is a perspective view. Fig. 2 is a longitudinal vertical section; and Fig. 3 is a perspective view of the dasher detached.

15 Similar letters of reference indicate corresponding parts in all the figures.

My invention has relation to churns with a vertical dasher having a rotary reciprocating motion; and it consists in the combination, 20 with the churn-frame, and its hinged covers supporting the mechanism for operating the dasher, of two detachable cylindrical vessels, one inserted inside of and resting with its upper rim or flange upon the other, and the inner 25 one of which forms the cream-containing vessel, substantially as hereinafter more fully set forth, and particularly pointed out in the claim.

In the annexed drawings, A A are the side pieces of the outer frame or support, which are 30 united opposite to and parallel to each other by the bottom A'.

Hinged upon the side pieces, A A, are half-covers B B, one of which carries the operating mechanism composed of a segment, C, having 35 teeth which mesh with a bevel-pinion, D, the shaft of which is mounted in a bearing in the cover, and projects on the inner side thereof, where it forms a square head, E.

F is a cylindrical can, made of sheet metal 40 and of such a size that it will fill up the space between the side pieces, A A. This can has a central step or bearing, G, in the center of its bottom, which receives a gudgeon, H, projecting downwardly from the center of the bottom 45 of an inner cylinder, I, of smaller diameter than cylinder F, so as to be readily inserted into it and leave a space, x, all around its sides and bottom. The upper rim of this inner cylinder, I, is turned down to form an annular

flange, i, which is soldered upon a square plate 50 or collar, K, fitting tightly between the side walls, A A, and having an upturned edge or flange, l, the two sides of which impinge upon the wooden side pieces, A A, and the two opposite sides upon the sides of the covers B B 55 when closed. The inner edge of collar K has a short tube, l, which projects down into the space x between the inner and outer cylinder, and the outer cylinder, F, has a faucet, m, on one side, through which its contents may be 60 drawn off.

The dasher is composed of an upper and a lower cross, L L', the ends of which are connected by vertical arms or beaters M, and the upper cross has a square socket in its center 65 to receive the square head of shaft E when covers B B are closed down, while the lower cross has a gudgeon, N, which is stepped into a central cup-shaped bearing in the bottom of the inner cylinder, I. 70

By making the supporting-frame A A' A open at both ends, cylinder F, with its inner cylinder, I, may be inserted sidewise instead of from the top. One or more sets of these 75 double cylinders may be used with a single frame, and when removed from the frame, or when not in use for churning, they may be used as creaming-cans, the space between the inner and outer cylinders being filled with pounded ice, or a stream of cold water being 80 kept running through the inlet l and out at the bottom through faucet m, or vice versa. When this method is used several cans may be connected into a system, the water running 85 from one to the other through the series during the operation of raising the milk. When the cream has "set" the milk may be drawn off through a short pipe in the bottom of the can, stopped with a cork or screw-plug, when the can is removed to the churn-frame with its 90 contents, to which more may be added from the other cans ready for churning.

Having thus described my invention, I claim and desire to secure by Letters Patent of the United States—

The rotary churn herein described, consisting of the open-sided case A, the cylinder F, removably placed therein at will, the cylinder

I *i*, adapted to be received within the cylinder F, and form a water space between, with inlet and outlet apertures, the oscillating dasher M L L', having slot E, and the hinged covers B B, 5 carrying the operating mechanism, the whole constructed, arranged, and combined to operate as and for the purposes set forth.

In testimony that I claim the foregoing as my own I have hereto affixed my signature in presence of two witnesses.

JOHN T. ESTABROOK.
